(57) **CLAIM**

The ornamental design for a dual monitor, as shown and described.

DESCRIPTION

FIG. 1 is a front, right, and top perspective view of a dual monitor, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a front elevational view thereof when being folded; and,

FIG. 10 is a rear elevational view thereof when being folded. The short-dash long-dash broken lines and reference numbers in FIGS. 1, 2, and 7 represent the extents of the detail views and form no part of the claimed design. The even-dash broken lines in the drawings illustrate portions of the dual monitor and form no part of the claimed design.
